STRING-CONTROLLED WHEELED TOY

Raymond Lohr, Erie, Pa., assignor to Louis Marx & Company, Inc., New York, N. Y., a corporation of New York

Application January 3, 1938, Serial No. 183,071

10 Claims. (Cl. 46—210)

This invention relates to toys, more particularly wheeled toys, and especially to a self-propelled toy the steering of which may be controlled by a string.

5 The primary object of the invention is to generally improve wheeled toys, and to add to the amusement value thereof. The wheeled toy may simulate a vehicle, or an animal, or the like, and several examples are disclosed herein. Children 10 enjoy the erratic steering movements which may be obtained under their own direct control through the control string, and, inasmuch as the control is by means of a very slight and unnoticeable upward movement of the string, the operation 15 is somewhat baffling and mystifying to observers. In the case of an animal toy simulating, for example, a pet dog, the control string may extend to the collar of the toy in simulation of a leash, and the toy is sensitively guided in one 20 direction or another through the simulated leash.

The foregoing object is fulfilled as follows. The toy is self-propelled by motor driven driving wheels, about which the toy body may oscillate. The toy body is unbalanced and the heavier end 25 normally moves toward the ground, where it is supported by suitable means during normal running of the toy. The control string is attached to the heavier end of the toy and extends upwardly far enough to be held in the hand of a person walking along with the toy. The toy is 30 readily steerable by raising the string slightly and thereby elevating the heavier end of the toy and the support means from the floor.

To the accomplishment of the foregoing and 35 other objects which will hereinafter appear, the invention consists in the toy driving, steering, and control elements, and their relation one to the other, as hereinafter are more particularly described in the specification and sought to be defined in the claims. The specification is accompanied by a drawing in which:

Fig. 1 is a side elevation of a simulated vehicle toy embodying features of the invention;

Fig. 2 is a bottom plan view thereof;

40 Fig. 3 is a partially sectioned side elevation of a simulated animal toy embodying a modified form of the invention;

Fig. 4 is a section taken in the plane of the line 4—4 of Fig. 3; and

50 Fig. 5 is a partially sectioned side elevation illustrating a modified form of the invention.

Referring to the drawing, the illustrated toys comprise driving wheels D driven by an appropriate motor generally designated M. A toy body B is mounted on appropriate support means in-

cluding the driving wheels D and also including a support generally designated S, said support being located at the heavier end of the toy and normally resting on the ground during operation of the toy. A control string C extends from the 5 heavier end of the toy upwardly far enough to be held in the hand of a person walking along with the toy. By slightly raising or tensioning the control string, the toy is oscillated about the driving wheels D, thus lifting the support S from the 10 ground. The toy is then readily steered in a new direction either by means of special steering wheels or by simply using the string itself to cause a swinging movement of the toy about the driving wheels D. 15

Considering the toy in greater detail, and referring first to the toy shown in Figs. 1 and 2, the driving wheels D are mounted on an axle 12 carried in a conventional motor frame 14. A winding stem 16 projects from the motor frame 14 through a suitable opening 18 in the side wall of the body B. It will be understood that an appropriate driving spring is connected to winding stem 16 and that a train of gearing is provided between the winding stem and the axle 12, all in 20 accordance with conventional practice.

The body B in this case simulates an automobile. The rear or controlling end is the heavier end, and the control string C is attached to that end. Each end of the toy is provided with a 25 biased axle, as is clearly shown in Fig. 2. The rear axle 20 and the front axle 22 may be substantially alike, these carrying freely rotatable wheels 24 and 26. In the present case, the support of the axles is obtained by simply passing 30 the same through the side walls of the body B.

It will be understood, from inspection of Fig. 2, that the toy will be steered in the direction of the arrow 28 when running on the driving wheels and rear wheels 24, whereas it will be steered in 35 a wholly different direction, specifically, the direction of the arrow 30, when running on the driving wheels D and the front wheels 26. It will also be seen, from inspection of Fig. 1, that the wheels 26 are elevated above the ground when 40 the toy rests on the wheels 24. This is the normal running position and is indicated in Fig. 1 by solid lines. When the control string C is elevated, the toy is oscillated about the driving wheels D from the solid line position to the broken line position. At this time, the rear wheels 24 are raised from the ground to the position 24', and the wheels 26 are lowered to rest on the ground as shown at 26'. The toy thus follows an erratic course, steering itself to either the right or left, 45 50 55

depending upon the operation of the control string C. Inasmuch as the movement of the string and the consequent oscillation of the toy may be limited to a small amount, it is not readily detected, particularly so because the toy is observed from above, and the erratic steering action is both amusing and puzzling to the uninitiated.

Referring now to Figs. 3 and 4, the toy where shown simulates a scotty dog. The toy is, in 10 many respects, of already known type, it including a pair of preferably fuzzy front paws 32 which project through slots 34 in the forward end of the toy body, and which are moved by oppositely directed cranks 36 and 38, at opposite ends of a 15 crankshaft 40, driven through appropriate gearing 42 by the regular driving motor of the toy. Driving wheels D are mounted on an axle 44 which is also driven by the motor. The motor is a spring motor of conventional type, and need 20 not be described in detail, it being sufficient to say that it may be wound by a conventional winding stem 46, the latter having the usual spiral ribbon spring connected thereto and being geared by appropriate gears to both the axle 44 and the 25 crankshaft 40. It may be mentioned that the front paws 32 do not actually move the toy but simply oscillate in elliptical paths at a rapid rate so that the toy appears to patter along on the ground although the actual propulsion is through 30 the driving wheels rather than the paws 32.

The toy is unbalanced and the tail end is the heavier end, it normally moving toward and resting on the ground during operation of the toy. The support means S on which the toy rests may 35 be simple stationary supports simulating short, stubby rear legs. If desired, they may be made to oscillate back and forth, as is done in certain known toys, but, in such case, they do not contribute to the actual drive of the toy, and the 40 bottom surface thereof is made such as to slide readily on the running surface 50. It will also be understood that the support S may, if desired, take the form of a small idle wheel, thus making the operation substantially frictionless.

45 The toy is controlled by a string C which, in order to give the toy a funny appearance, is attached at the end of a simulated tail 52, the latter being made of sheet metal fixedly secured to the toy body. When the string is raised, the 50 toy is tilted about the wheels D, thus raising the support S from the running surface 50. At this time, the toy very readily swings to one side or another about the driving wheels D, and the slightest movement of the upper end of the control string causes a complete change in direction 55 of operation of the toy. By again lowering the string slightly, the toy rests on support S and runs forwardly in the normal direction, which may be made straight or curved, as desired.

60 A modified form of toy simulating a scotty dog is illustrated in Fig. 5. This modification is desirable for purchasers who seek realism rather than comical appearance. In this case, the driving wheels are shifted from the forward toward 65 the rear end of the toy. The unbalance of the toy is such that the head end normally moves downwardly toward the running surface 50. At the forward end, the toy rests on a small, inconspicuous wheel 68, this wheel preferably being located 70 between the front paws 62, which are rapidly oscillated and reciprocated by crank mechanism 64, just like that described in connection with Fig. 3. Both the driving wheel axle 66 and the crank 64 are driven by conventional spring motor mechanism the winding stem of which is indicated at 75

Here again, the control string is attached to the heavier end of the toy and a realistic appearance is obtained by treating the string as a leash, the lower end of the string being connected to a simulated collar 70 on the neck of the dog. The 5 tail 72 may, in this case, be made of fabric or other flexible material capable of wagging during operation of the toy.

It is believed that the operation of the toy will be understood from the description heretofore given. The toy normally runs along on the driving wheels D and the front wheel 60. The paws 62 appear to patter along as the toy runs along the surface 50. The normal direction of operation is preferably straight, but it may be curved, 15 as by giving the front wheel 60 an angular position. Whenever it is desired to change the direction of the toy, the child simply tensions the string somewhat, thus elevating the wheel 60 slightly from the ground, whereupon the toy 20 swings to one side or the other under the control of the string. The amount of string movement needed for control of the toy is very slight and the operation of the toy is, therefore, not at all apparent to those watching the same. 25

It is believed that the construction and operation, as well as the many advantages of the toys embodying the present invention, will be apparent from the foregoing detailed description thereof. It will also be apparent that, while I have 30 shown and described the invention in preferred forms, many changes and modifications may be made in the structures disclosed without departing from the spirit of the invention defined in the following claims. 35

I claim:

1. A self-propelled wheeled toy comprising a driving wheel, a motor for driving continuously said wheel in one direction, a toy body, said body being permanently unbalanced toward one end 40 so that the heavier end normally moves toward the floor, means supporting the heavier end, a control string attached to the heavier end and extending upwardly far enough to be held in the hand of a person walking along with the toy, 45 whereby said toy is readily steerable by raising the string and thereby elevating the support means from the floor.

2. A self-propelled wheeled toy comprising driving wheels remaining constantly on the floor, 50 a spring motor for continuously driving said wheels in one direction, a toy body carried by the wheels, said body being permanently unbalanced toward one end so that the heavier end normally moves toward the floor, means supporting the heavier end, a control string attached to the heavier end and extending upwardly far enough to be held in the hand of a person walking along with the toy, whereby said toy is readily steerable by raising the string and 60 thereby elevating the support means from the floor.

3. A self-propelled wheeled toy comprising a driving wheel, a motor for continuously driving said wheel in one direction, a toy body, said body 65 being permanently unbalanced toward one end so that the heavier end normally moves toward the ground, support means on which the heavier end rests during normal running of the toy, a steering wheel at the opposite end of the toy, 70 said latter steering wheel being turned in a different direction and being normally elevated from the ground, a control string attached to the heavier end and extending upwardly far enough to be held in the hand of a person walk- 75

ing along with the toy, whereby said toy is readily steerable by raising the string and thereby elevating the heavier end of the toy until the toy runs on the steering wheel at the lighter end.

5 4. A self-propelled wheeled toy comprising a driving wheel, a motor for continuously driving said wheel in one direction, a toy body, said body being permanently unbalanced toward one end so that the heavier end normally moves toward the ground, a steering wheel on which the heavier end rests during normal running of the toy, a steering wheel at the opposite end of the toy, said latter steering wheel being turned in 10 a different direction and being normally elevated from the ground, a control string attached to the heavier end and extending upwardly far enough to be held in the hand of a person walking along with the toy, whereby said toy is readily steerable by raising the string and thereby elevating the heavier end of the toy, so that the toy runs on the steering wheel at the lighter end instead of the steering wheel at the heavier end.

25 5. A self-propelled wheeled toy comprising driving wheels remaining constantly on the ground, a spring motor for continuously driving said wheels in one direction, a toy body carried by the wheels, said body being permanently unbalanced toward one end so that the heavier 30 end normally moves toward the ground, a steering wheel on which the heavier end rests during normal running of the toy, a steering wheel at the opposite end of the toy, said latter steering wheel being turned in a different direction and being normally elevated from the ground, a control string attached to the heavier end and extending upwardly far enough to be held in the hand of a person walking along with the toy, whereby said toy is readily steerable by raising the string and thereby elevating the heavier end of the toy, so that the toy runs on the steering wheel at the lighter end instead of the steering wheel at the heavier end.

35 6. A self-propelled wheeled toy comprising a driving wheel, a spring motor for continuously driving said wheel in one direction, a toy animal body carried by the wheel, simulated legs on said body, the body being permanently unbalanced so that one end normally moves toward the ground, means supporting the heavier end, a control string attached to the heavier end and extending upwardly far enough to be held in the hand of a person walking along with the toy, whereby said toy is readily steerable by raising the string and thereby elevating the support means from the ground.

40 7. A self-propelled wheeled toy comprising a driving wheel, a motor for continuously driving said wheel in one direction, a toy animal body carried by the wheel, a pair of paws projecting

forwardly from the body, means within the body actuated by the motor for moving said paws in a lifelike manner, the body being permanently unbalanced so that the heavier end normally moves toward the floor, means supporting the 5 heavier end, a control string attached to the heavier end and extending upwardly far enough to be held in the hand of a person walking along with the toy, whereby said toy is readily steerable by raising the string and thereby elevating 10 the support means from the floor.

8. A self-propelled wheeled toy comprising driving wheels remaining constantly on the ground, a spring motor for continuously driving said wheels in one direction, a toy animal body 15 carried by the wheels, a tail projecting at the end of the body, a pair of dummy paws projecting forwardly from the body above the ground, crank means within the body actuated by the spring motor for moving said paws in a lifelike manner, 20 the body being so unbalanced that the tail end normally moves toward the ground, means supporting the heavier end, a control string attached to the tail and extending upwardly far enough to be held in the hand of a person walking along with the toy, whereby said toy is readily steerable by raising the string and thereby elevating the support means from the ground.

9. A self-propelled wheeled toy comprising a driving wheel, a motor for continuously driving 30 said wheel in one direction, a toy animal body carried by the wheel, a pair of paws projecting forwardly from the body, means within the body actuated by the motor for moving said paws in a life-like manner, the body being permanently 35 unbalanced so that the head end normally moves toward the floor, a control string attached to the head end and extending upwardly far enough to be held in the hand of a person walking along with the toy, whereby said toy is readily steerable by raising the string, and thereby elevating the head end of the toy.

10. A self-propelled wheeled toy comprising driving wheels remaining constantly on the ground, a spring motor for continuously driving 45 said wheels in one direction, a toy animal body carried by the wheels, a pair of dummy paws projecting forwardly from the body above the ground, crank means within the body actuated by the spring motor for moving said paws in a 50 lifelike manner, the body being permanently unbalanced so that the head end normally moves toward the ground, a guide wheel near the front end of the toy, a control string attached at the collar of the animal and extending upwardly 55 far enough to be held in the hand of a person walking along with the toy, whereby said toy is readily steerable by raising the string, and thereby elevating the guide wheel from the ground.

RAYMOND LOHR. 60
